MAGIC DISPLAY APPARATUS

Peter Lamonte, New York, N. Y., assignor of one-third to Leo Wishin, one-third to Bernard Wishin, both of New York, N. Y., and one-third to Fred M. Heyman, Brooklyn, N. Y.

Application November 6, 1934, Serial No. 751,701

7 Claims. (Cl. 40—33)

This invention relates to a magic display apparatus.

The object of the invention is the production of a magic display apparatus, wherewith a display housing is alternately shown to be empty and then shown to contain different objects, without an observer being able to see how the different objects are placed into and removed from the display housing.

10 The second object of the invention is the production in a magic display apparatus, of a main housing having a display housing therein and a working chamber at the rear of the display housing, the latter being invisible by the reflection of mirrors in the main housing.

15 The third object of the invention is the production in a magic display apparatus, of a main housing, with strips on a portion of the upper face of its base plate and on a portion of the lower face of its ceiling or roof, which strips by means of mirrors are reflected to indicate that said strips cover the full area of said base plate and said ceiling.

20 The fourth object of the invention is the production of a magic display apparatus, which may be used for a show window, for amusement in a theater, for a toy and for other purposes.

25 Referring to the drawings, Fig. 1 shows a front view of the magic display apparatus; Fig. 2 represents a section of Fig. 1 on the line 2—2; Fig. 3 indicates a section on the line 3—3 of Fig. 1; Fig. 4 shows a partial section of Fig. 1 on the line 4—4; Fig. 5 is an enlarged section on the line 5—5 of Fig. 3; Fig. 6 shows a section on the line 6—6 of Fig. 3; Fig. 7 represents a front view of a portion of Fig. 5; Fig. 8 shows a section on the line 8—8 of Fig. 5; Fig. 9 shows a partial left hand view of Fig. 7 and Fig. 10 shows a diagrammatic top view of the interior of the main housing of the apparatus with some of its appurtenances therein.

30 The magic display apparatus in the present exemplification comprises a main housing designated in its entirety by the numeral 20. The said housing 20 is shown with the base plate 22, preferably of wood, and around which latter extends the metallic band 23. Corner posts 25 extend upwardly from the base plate 22 and have their lower ends fastened thereto. A pair of side walls 26 each extend between the posts 25. A roof or ceiling 28 is supported at the upper ends of the posts 25. A pair of electric light bulbs 31 and 32 extend up from the base plate 22 and an electric light bulb 33 extends downwardly from the ceiling 28.

35 Within the housing 20 are indicated the inclined walls 38 which extend between the base plate 22 and the ceiling 28, and make angles of forty-five degrees with the side walls 26. The forward ends of the walls 38 are joined by the connecting member 39 which is at right angles to the side walls 26 and has indicated therein the opening 40 with the stop face 40a.

40 Mirrors 41 and 42 extend over the inclined walls 38. The walls 38 divide the interior of the housing 20 into the observation chamber 43 and the working chamber 44.

45 A display housing designated in its entirety by the numeral 45 is positioned within the main housing 20 and connects the observation chamber 15 43 and the working chamber 44. The display housing 45 comprises the base plate 46 having the front flange 47, the side walls 48, and the roof or ceiling 49. The rear of the display housing 45 has an opening 50, and at the front of the said 20 housing which is open are shown the swinging doors 55. The doors 55 are fastened to the rods 56. A lower tubular support 59, having the longitudinal rear opening 60, extends between the base plates 22 and 46 and a similar tubular support 63 with its longitudinal rear opening 64 25 extends between the roofs 28 and 49.

50 The longitudinal axis of the supports 59 and 63 are in line with peak of the mirrors 41 and 42.

An opening 65 is indicated in the front face of 30 the support 59. The front ends of the mirrors 41 and 42, at their upper and lower ends meet within the openings 60 and 64 at the vertical center line of the housing 45. A stair case 68 connects the base plates 22 and 46. 35

55 In the lower tubular support 59 is positioned the vertical oscillating bar 70, having its ends pivoted in the base plates 22 and 46.

60 To the lower ends of the rods 56 are fastened the pinions 74 which mesh with the spur gears 45 75 that are journaled on pins extending from the lower face of the base plate 46. A lever 76 has its ends pivoted to pins extending from the spur gears 75. An arm 78 having the forked end 79 has one end fastened to the oscillating bar 70 45 and its forked end 79 engages a pin 80 extending from the lever 76. An operating lever 82 has one end fastened to the vertical oscillating bar 70. At the swinging end of the operating lever 82 50 is journaled the roller 83. The said lever 82 extends through the opening 40, and a spring 84 has one end fastened to the lever 82 and its other end is fastened to one of the inclined walls 38.

65 A supporting plate 88 is fastened to the base plate 22 in the working chamber 44. The electric 55

motor 90 having the armature shaft 91 is positioned in the working chamber 44 and is fastened to the plate 88.

A gear housing for the electric motor is indicated at 92, and contains a pair of gears, not shown, one of which is fastened to the armature shaft 91 in the usual way. A worm shaft 96 extends from the other gear in said gear housing and has connected thereto the worm 97. A driving shaft 98 is journaled in journal brackets 99 extending upwardly from the plate 88. A worm wheel 100 in mesh with the worm 97 is fastened to one end of the shaft 98, and a cam 101 is fastened to the other end of the shaft 98. A main disc cam 105 having the side cam 107 extending therefrom is fastened to the driving shaft 98. A roller 108 is journaled to the cam 106. The roller 83 coacts with the side cam 107. A vertical shaft 110 in the working chamber 44 has its upper end journaled in the journal bracket 111 extending from the roof or ceiling 28, and its lower end is journaled in the journal bracket 112 extending up from the supporting plate 88. To the shaft 110 are fastened the pinion 114 and the controlling disc 115 having the four locking notches 116, which latter are ninety degrees apart. To the supporting plate 88 is fastened the guide bracket 118 having the guide lugs 119 at its ends. A slide 122 having the hook end 123 is guided in the bracket 118 and the guide lugs 119. The roller 108 coacts with the hook end 123.

From the supporting plate 88 extends the pin 128, on which is hinged the locking lever 130 having extending therefrom the locking pin 131 and the stop pin 132. The locking pin 131 is adapted to lock with the locking notches 116 and the stop pin 132 is adapted to bear against the circumferential surface of the controlling disc 115. A spring 134 has one end hinged to a pin 135 extending from the plate 88, and its free end bears against the lever 130. A stop pin 136 for the spring 134 also extends from the plate 88.

From the plate 88 extends the boss 140. To the upper end of the boss 140 are journaled the spur gear 141 and the pin disc 142, which may be integral with each other or connected to each other. Locking pins 143 extend from the disc 142. The spur gear 141 meshes with the pinion 114.

50 A pair of guide brackets 146 and 147 extend from the supporting plate 88 and have guided therein the slide bar 148 having the bifurcated end 149, in which latter is journaled the roller 150. The roller 150 coacts with the cam 101. A pin 151 extends from the slide bar 148 and a spring 152 has one end fastened to the pin 151 and its other end is fastened to the guide bracket 147. A pawl 154 having the hook end 155 is pivoted on the pin 156 extending from the slide bar 148. A plate spring 158 has one end fastened to the slide bar 148 and its free end bears against the pawl 154. The hook end 155 coacts with the locking pins 143. Adjacent to the upper end of the vertical shaft 110 is fastened the upper cross shaped journal bracket 162 having the pairs of ears 163, and adjacent to the lower end of the shaft 110 is fastened the lower cross shaped journal bracket 164 having the pairs of ears 165.

70 In the working chamber 44 are indicated four movable walls designated respectively by the numerals 170, 171, 172 and 173. Each of said walls 170 to 173 has extending therefrom the supporting platform 174. Adjacent to the upper 75 end of each of said walls is fastened a bifurcated

journal bracket 175, and at the lower portion of each of said walls are fastened the pair of guide brackets 176 and 177. In each pair of the guide brackets 176 and 177 is guided the slide rod 178. A bifurcated journal bracket 179 is fastened to each of the slide rods 178. A single lever 185 for each of the walls 170 to 173, has its upper end pivoted to a pair of the ears 163 of the upper cross shaped journal bracket 162. The lower end of each of the single levers 185 is pivoted to the bifurcated journal bracket 179. A pair of spaced parallel levers 186, having the lower portions 187 inclined to the body portions thereof for each of said walls, have each their upper ends pivoted to one of the journal brackets 175 by means of the pivot pin 188. A spacer disc 189 is supported on each of the pins 188 and positioned between the levers 186. To the ends of the lower portions 187 are pivoted the guide rollers 193, which latter coact with the main disc cam 106. Between each pair of the levers 186 is journaled a roller 195 which coacts with its accompanying single lever 185.

Each pair of the levers 186 at the lower portions thereof are pivoted to a pair of the ears 165 of the brackets 164, by means of the pivot pin 197. It will be noted that each single lever 185 is positioned between its accompanying pair of levers 186.

A spring 198 connects the upper ends of each oppositely positioned pair of single levers 185, and a spring 199 connects the lower ends of each of the pairs of levers 186.

Referring to Figs. 1, 2, 3, 4 and 10, on the upper face of the base plate 22 in the observation chamber 43, are indicated a plurality of strips designated in their entirety by the numeral 200, and on the bottom face of the roof or ceiling 28 in said observation chamber 43, are indicated a plurality of similar strips designated in their entirety by the numeral 201.

The strips 200 comprise, the pair of strips 205 and the oppositely positioned pair of strips 206, the pair of strips 207 and the oppositely positioned pair of strips 208, the pairs of strips 209, 210, 211 and 212, and the single strips 213 and 214. Some of the strips extend from the side walls 26 of the main housing 20 and some from the front end of the base plate 22 to the lower tubular support 59. The strip 213 is adjacent to the lower edge of the mirror 41 and the strip 214 is adjacent to the lower edge of the mirror 42.

By means of the light of the electric light bulb 31 and the mirror 41, the strip 213 is reflected as indicated at 213a (Fig. 10), and the pair of strips 205 are reflected as indicated at 205a. The electric light bulb 31 is reflected at 31a.

By means of the light of the electric light bulb 32 and the mirror 42, the strip 214 is reflected as indicated at 214a (Fig. 10) and the pair of strips 208 are reflected as indicated at 208a. The electric light bulb 32 is also reflected at 32a. By means of the reflection the strips 209, which may be pieces of tape or may be painted on base plate 20, an appearance is produced that the strips 209 extend to the rear of the main housing 20 and that there is an electric light bulb 31a near its rear portion, which in reality does not exist. The strips 201 are reflected at the top of the observation chamber 43, as described for the strips 200.

Referring particularly to Fig. 10, the top face of the roof 49 of the display housing 45 has indicated therein the triangular shaped ornamentation having the base 220 and the side 221, the triangular shaped ornamentation having the base 75

223 and the side 224, and the triangular shaped ornamentation 226. By means of the mirror 41 and the electric light bulb 31, the side 221 is reflected at 221a and the base 220 is reflected at 220a. By means of the mirror 42 and the electric light bulb 32 the side 224 is reflected at 224a, and the base 223 is also reflected at 220a. The results of the reflections make it appear that there is a triangular shaped ornamentation opposite the ornamentation 226 and which in reality does not exist.

To operate the magic display apparatus, the swinging doors 55 of the display housing 45 may be considered open. The electric light bulbs 31, 32 and 33 are energized and the electric motor 90 is started. The supporting platform 174 of the wall 170 has nothing indicated thereon, the platform 174 of the wall 171 has indicated the top view 230 of a doll, the platform 174 of the wall 173 has supported thereon a container 231 and the platform 174 of the wall 172 has supported thereon a bottle 232. The observer as he views the open display housing 45 will note that it is empty, and that the main housing 20 is empty, appearing as a rectangular enclosure with the strips 200 and 201, and the electric light bulbs 31 and 32 reflected as already described.

With the rotations of the electric motor 90 the worm 97 is turned. The latter turns the worm wheel 100, and thereby the driving shaft 98 turns. The cams 101, 106 and 107 turn with the shaft 98. The rotations of the cam 101 moves the slide bar 148 in the direction of the arrow A and said bar is moved in the opposite direction by the tension of the spring 152. When the slide bar 148 moves in the direction of the arrow A, the hook end 155 of the pawl 154 engages the pins 143 of the pin disc 142, one after the other. By this means the disc 142 is turned in the direction 40 of the arrow B. The spur gear 141 turns with the disc 142. The spur gear 141 turns the pinion 114 in the direction of the arrow C and the vertical shaft 110 turns with the said pinion 114 in the direction of the arrow C. The controlling disc 115 turns with the vertical shaft 110, and is placed in four different positions ninety degrees apart, and held in place by virtue of the locking pins 131 engaging the locking notches 116 one after the other. By this means the walls 170, 172, 173 and 171 are consecutively positioned opposite the opening 50 of the display housing 45. After the observer has viewed the empty display housing 45, the rotation of the side cam 107 and the tension of the spring 84, the oscillating lever 82 is swung and brought to bear on the stop face 49a of the opening 49 to open the doors 55, the required amount not more than 135 degrees from their closed positions.

With the swing of the lever 82, the arm 78 moves the lever 76 which turns the spur gears 75, whereby the pinions 74 are turned, and thereby the doors 55 are swung open. When the roller 83 coacts with the side cam 107, the operating lever 82 with its coacting elements closes the doors 55. After the doors 55 are closed the vertical shaft 110 remains at rest for an interval of time and taking into consideration the wall 170, the tension of the springs 198 and 199 draws the wall 170 to its open position from the opening 50. The roller 108 strikes the hook end 123 of the slide 122, which disengages the locking lever 130 from its locking notch 116 of the disc 115, and by means of the rotation of the driving shaft 98 and the intermediate elements the shaft 110 is turned 75 as already described and the wall 172 is positioned

opposite and in line with the opening 50. At the same time the controlling disc 115 is locked in position by means of the tension of the spring 134 bearing against the lever 130. The main disc cam 106 now bears against the roller 103 and the pair of levers 186 of the wall 172 move the said wall 172 opposite the opening 50. The side cam 107 coacting with the roller 83 opens the doors 55 as already explained. The bottle 232 is now brought into view. The door 55 are now again closed, the wall 172 is moved from the opening 50, the controlling disc 115 is again unlocked, the shaft 110 is again turned, the controlling disc 115 is again locked and the wall 173 moves opposite the opening 50. The doors 55 again open 15 and the container 231 is brought into view. In the same manner the doll 230 is brought into view in the display housing 45.

It will be noted that the stop pin 132 controls the distance to which the locking pin 131 enters 20 the locking notches 116.

The magic display apparatus when used for amusement in a theatre is made large enough so that the supporting platforms 174 may support human beings and various large objects. 25

Various modifications may be made in the invention and the present exemplification is to be taken as illustrative and not limitative thereof.

Having described my invention, I claim:

1. In an apparatus the combination of a display housing having an opening in the rear portion thereof, a pair of doors hinged to said housing opposite to its opening, means to open and close said doors, a plurality of walls supported outside of said housing and to the rear of its opening and means to revolve said walls and position them one after the other to close said opening. 30

2. In an apparatus the combination of a main housing, comprising a base plate, a roof and side walls, a pair of mirrors inclined to each other and to said side walls in said housing, a pair of electric light bulbs extending up from said base plate in front of said mirrors and strips indicated on the upper face of said base plate in front of said mirrors, said electric bulbs and strips reflected by said mirrors, to make it appear that strips and an electric light bulb are provided for the rear portion of the housing. 45

3. In an apparatus the combination of a main housing, a base plate and a roof for said housing, side walls connecting said base plate and roof, inclined vertical walls extending between said base plate and roof and each making an angle of forty five degrees with its adjacent side wall, a mirror bearing against each of said inclined walls with their inner edges adjacent to each other at the central portion of said main housing, a pair of electric bulbs extending from said base plate at the front portion thereof and strips indicated on the upper face of said base plate and on the lower face of said ceiling in front of said mirrors, a number of said strips and said electric light bulbs reflected by said mirrors, to make it appear that strips and an electric light bulb are provided for the rear portion of said housing. 55

4. In an apparatus the combination of a main housing, comprising a base plate, a roof and side walls, vertical mirrors inclined to each other and to said side walls in said main housing, dividing it into an observation chamber at its front portion and into a working chamber at its rear portion, a display housing having its vertical center line at the peak of said mirrors, a pair 70

of side walls for said display housing, a pair of doors at its front end, said display housing having an opening at its rear, walls in the working chamber adapted to close the opening in said display housing, a roof for said display housing, ornamentations indicated on the latter roof in said observation chamber and to the front of said mirrors and electric light bulbs in said main housing in front of said display housing, said 10 mirrors reflecting said ornamentations to make it appear that they are indicated to the rear of said mirrors.

5. In an apparatus the combination of a main housing, a base plate and a roof for said housing, side walls connecting said base plate and roof, inclined vertical walls extending between said base plate and roof and each making an angle of forty-five degrees with its adjacent side wall, said inclined walls producing an observation chamber in the front portion of the housing and a working chamber in the rear portion thereof, a mirror bearing against each of said inclined walls with their inner edges adjacent to each other at the central portion of said main housing, a pair of electric light bulbs extending up from said base plate in said observation chamber, a single strip indicated on the upper face of said base plate in said observation chamber parallel to and adjacent to the lower edge of each mirror, a similar single strip indicated on the lower face of said roof in said observation chamber parallel to and adjacent to the upper edge of each of said mirrors, a plurality of pairs of strips both in the said base plate and roof of said housing in said observation chamber, said single strips reflected by said mirror to appear as double strips and said electric light bulbs reflecting as one bulb appearing in the rear of said mirrors and a number of said pairs of strips reflected by 40 said mirrors to make them appear in the rear portion of said housing.

6. In an apparatus the combination of a main housing, a base plate and a roof for said main housing, side walls between said base plate and roof, inclined vertical walls extending between said base plate and roof, each of the latter walls making an angle of forty-five degrees with its adjacent side wall, said inclined walls at their front ends having a connecting member, said inclined 45 walls producing an observation chamber in the front portion of said main housing and a working chamber in the rear portion thereof, a mirror bearing against each of said inclined walls and having their inner edges adjacent to each other at the central portion of the main housing, a display housing in the main housing having its vertical axis at the peak of said mirrors and connecting the observation chamber and said working chamber, a base plate, side walls and a roof 50 for the display housing, the front and rear of the display housing each having an opening, means to close said rear opening, rods rotatively supported at the open front end of the display housing, a door connected to each of said rods, a tubular support having a longitudinal rear opening extending between the base plates of the main housing and the display housing, and a similar support between the roofs of the main housing and display housing, an electric motor in the working chamber, a cam actuated by said motor, an oscillating bar in the lower tubular support of said display housing, a pinion fastened to the lower end

of each of said rods, spur gears journaled to the lower face of the base plate of the display housing in mesh with said pinions, a lever having its ends pivoted to said spur gears, a pin extending from said lever, an arm having one end fastened to the oscillating bar, a fork at the other end of said arm engaging the pin of said lever, an operating lever having one end fastened to said oscillating bar, and a roller journaled to the swinging end of the operating lever, the latter extending 10 through an opening in the connecting member of the inclined walls, and a spring having one end connected to the latter lever and its other end fastened to one of said inclined walls, the roller coacting with the cam to open the doors of the 15 display housing and the tension of said spring automatically closing said doors.

7. In an apparatus, the combination of a main housing, a base plate and a roof for said housing, side walls between said base plate and roof, inclined vertical walls extending between said base plate and roof, each of the latter walls making an angle of forty-five degrees with its adjacent side wall, said inclined walls at their front ends having a connecting member, said inclined walls producing an observation chamber in the front portion of said main housing and a working chamber in the rear portion thereof, a mirror bearing against each of said inclined walls and having their inner ends adjacent to each other at the central portion of the main housing, a display housing in the main housing having its vertical axis at the peak of said mirrors and connecting the observation chamber and said working chamber, a base plate, side walls and a roof for the display housing, 35 the front and rear of the display housing each having an opening, doors for the opening at the front of the display housing, an electric motor in the working chamber, a vertical shaft journaled in the working chamber to the rear of said display 40 housing, means interposed between said motor and shaft to intermittently rotate the shaft by said motor, four movable walls in the operating chamber positioned to close the opening at the rear of the display housing one after the other with 45 the rotations of the vertical shaft, cross shaped journaled brackets fastened to said vertical shaft adjacent to its upper and lower ends, a slide rod slidably connected to each of said walls adjacent to the lower end thereof, a single lever for each of 50 said walls having its upper end pivoted to the journaled bracket at the upper end of the vertical shaft and its lower end in slidable relation with its adjacent slide rod, a pair of levers for each of said walls having their upper ends pivoted to its wall and their lower portions pivoted to the journal bracket at the lower portion of the vertical shaft, a spring connecting the upper portion of a single lever and the upper portion of a pair of 55 levers, a spring connecting the lower portion of a pair of levers with a second pair of the levers, a guide roller pivoted to the lower portions of the pairs of levers and a cam in the operating chamber turning with the rotations of said electric motor and coacting with the rollers at the 60 lower portion of said pairs of levers as the latter are intermittently brought in position with said cam to close said walls with their openings against the tension of said springs which open the walls from the rear opening of the display 65 housing.

PETER LAMONTE.
